UNITED STATES PATENT OFFICE.

CARL HENDERSON, OF CHICAGO, ILLINOIS, ASSIGNEE TO MIEHLE PRINTING PRESS & MANUFACTURING COMPANY, OF CHICAGO, ILLINOIS, A CORPORATION OF ILLINOIS.

SHEET-SEPARATOR BLOWER.

Application filed February 1, 1922. Serial No. 533,183.

To all whom it may concern:

Be it known that I, CARL HENDERSON, a citizen of the United States, residing at Chicago, in the county of Cook and State of Illinois, have invented certain new and useful Improvements in Sheet-Separator Blowers, of which the following is a specification.

This invention relates to means for positively insuring the injection of air or other separating medium into a pile of sheet material to facilitate separation of the sheets regardless of the angle at which the sheets may lie.

One object of this invention is to obviate the necessity of adjusting a sheet separator nozzle in connection with a pile of sheet material in which the sheets lay at different angles.

Another object is to provide a simple and efficient sheet separator nozzle for directing jets of air at different angles to insure separation of sheets in the pile regardless of the angles at which the different sheets in the pile may lie.

These and other objects are accomplished by means of the arrangement disclosed on the accompanying sheet of drawings, in which—

Figure 1 is a side elevation, partly in section, of my sheet separator nozzle, the section being taken through one set of nozzle apertures directed at an angle downwardly and taken in the plane of line 1—1 of Figure 2, a pile of sheet material also being shown to illustrate operation of the device;

Figure 2 is a front elevation of the same nozzle;

Figure 3 is a top plan view of the same nozzle;

Figure 4 is a fragmentary sectional view taken in the plane of line 4—4 of Figure 2; and

Figure 5 is a fragmentary sectional view taken in the plane of line 5—5 of Figure 2.

The various novel features of the invention will be apparent from the following description and drawings and will be particularly pointed out in the appended claims.

Referring to the figures of the drawings, it will be noted that the blower or nozzle takes the form of a casing 10 having two

vertical partitions 11 and 12 therein converging forwardly of the nozzle. The face 55 of the nozzle is provided with three sets 13, 14 and 15 of apertures arranged in different vertical planes and communicating respectively with chambers 16, 17 and 18 formed in the casing 10 by the partitions 60 12 and 11. Air or other separating medium is applied to the casing 10 through any suitable connection 19.

Referring particularly to Figure 1 a pile 20 of paper is shown, the sheets of which 65 may be in a horizontal plane as indicated at 21 or may curve upwardly as indicated by dotted lines 22, or may curve downwardly as indicated by dotted lines at 23. Obviously, a single nozzle having a single 70 opening or a plurality of openings pointing in the same direction and directing jets of air in the same direction could not possibly efficiently separate sheet material lying in the various angled positions indicated. To 75 make possible the separation of sheets by a blower under such conditions and without making adjustment of the nozzle to accommodate the peculiar lay of different sections of the pile, or of different piles having 80 sheets lying at different angles, I have provided the blower or nozzle herein shown in which the apertures 13, 14 and 15 are all directed in different general directions. For example, the apertures 14 are directed in 85 horizontal lines, as shown in Figure 4, and air jets issuing therethrough would be effective in separating sheets lying horizontally, as indicated at 21 in Figure 1. Apertures 13, as shown particularly in Figure 90 1, are directed angularly downwardly and are particularly effective in separating sheets curved upwardly at the edges, as indicated at 22 in Figure 1.

The apertures 15, as shown, particularly 95 in Figure 5, which extend angularly upwardly through which jets of air are forced, find particular application in cases where the sheets are curved downwardly at the edges, as indicated at 23 in Figure 1. Accordingly the jets of air issuing from the three sets of apertures 13, 14 and 15 are effective for separating the sheets regardless 100 of the angles in which the sheets generally lie, for such jets of air are directed straight 105 into the sheets and between same so that

minimum resistance is offered in lifting the sheets from the pile.

It is my intention to cover all modifications of the invention falling within the spirit and scope of the following claims.

I claim:

1. A separator for separating sheets in a pile comprising a casing one wall of which is provided with apertures extending in different directions whereby jets of air issuing therethrough are directed at angles with respect to each other.

2. A separator for separating sheets in a pile comprising a casing one wall of which is provided with apertures extending in different directions and partitions in said cas-

ing for forming compartments communicating with said apertures.

3. A separator for separating sheets in a pile comprising a casing having a front wall, and vertical partitions extending rearwardly from said front wall forming compartments in said casing, said front wall having apertures communicating with said different compartments and extending at different angles with respect to each other whereby jets of air issuing therefrom will be directed at angles with respect to each other.

Signed at Chicago, Illinois, this 28th day of December, 1921.

CARL HENDERSON.
